UNITED STATES PATENT OFFICE.

WILLIAM H. CLAY, OF PARIS, KENTUCKY.

SPLIT LINK.

SPECIFICATION forming part of Letters Patent No. 329,142, dated October 27, 1885.

Application filed March 27, 1885. Serial No. 160,327. (No model.)

To all whom it may concern:

Be it known that I, WILLIAM H. CLAY, of Paris, in the county of Bourbon and State of Kentucky, have invented a new and Improved 5 Splint Link, of which the following is a full, clear, and exact description.

My invention relates to a new and improved "lap" or "split" link for chains, &c.; and the invention consists in the peculiar construction and arrangement of parts, as hereinafter fully described, and pointed out in the claim.

Reference is to be had to the accompanying drawings, forming part of this specification, in 15 which similar letters of reference indicate corresponding parts in all the figures.

Figure 1 is a plan view of my new and improved link as it appears when closed. Fig. 2 is a sectional elevation of the same, taken on 20 the line $x-x$ of Fig. 1. Fig. 3 is a plan view of the link as it appears when open. Fig. 4 is a sectional elevation of the link, taken on the line $y-y$ of Fig. 1. Figs. 5 and 6 are plan and sectional views showing the link formed with 25 diagonal protuberances, and Fig. 7 is a side view showing the link open.

A represents my new and improved link. This is composed of two parts, a b , hinged together by the hinge c . The part a of the link is 30 for the most part made of half-round iron. It is open at a' , cut away at a'' , and formed upon its inner surface, opposite the opening a' , with the enlargement or protuberance a^3 . The part b of the link, like the part a , is for the most part 35 made of half-round iron. It is open at b' , cut away at b'' , and formed upon its inner surface, opposite the opening b' , with the enlargement or protuberance b^3 . The opening a' of part a stands at the opposite side of the link from 40 the opening b' of part b , and the enlargement a^3 of part a stands at the opposite side of the enlargement b^3 of part b , so that when the parts a b of the link are closed together the enlargements a^3 b^3 close the openings a' b' , and 45 thus form a complete and continuous link, as shown in Figs. 1 and 2. The cut-away places a'' b'' , when the parts of the link are closed together, form a V-shaped recess, as shown in Fig. 2, so that a nail or other small object

may be easily inserted between the parts of 50 the link for forcing it open in case it should stick or not work easily at the hinge.

In the form of link shown in Figs. 1, 2, 3, and 4 ends of the enlargements or protuberances a^3 b^3 are beveled, as shown at d , and the ends 55 of the parts of the link at the openings a' b' are oppositely beveled, as shown at d' , to fit the beveled ends of the enlargements or protuberances, as clearly shown in Fig. 2, so that tight joints will be formed at the openings in 60 the parts of the link when the link is closed, and in this form of link corresponding projections, c' , are formed on the parts a b of the link, which are fashioned to form the hinge c .

In the form of link shown in Figs. 5, 6, and 65 7 the projections c' are omitted, the hinge c being formed in the material composing the body of the link, and in this form of link the ends of projections a^3 b^3 are cut diagonal to the line or plane of the hinge c , and the ends 70 of the parts of the link that close against the projections or protuberances are cut at an opposite angle to fit the diagonal ends of the projections, as shown clearly in Figs. 5 and 6, so that the projections will prevent lateral movement of the parts of the link upon each other, 75 and thus prevent strain upon the hinge c .

By constructing the link with the hinge arranged as shown and described the small flanges or fins of metal which always form at 80 the inner edges of the parts of the link in the use and wear thereof in no manner interfere with the opening of the link, as such fins do with links that open and close edgewise with the parts of the link sliding upon each other. 85

Having thus described my invention, I claim as new and desire to secure by Letters Patent—

A link consisting of the parts a b , hinged together at the end to open away from each other, and each provided on its inner surface 90 with an enlargement or protuberance and an opening to receive the enlargement or protuberance, substantially as herein shown and described.

WILLIAM H. CLAY.
